VACUUM INSULATED CONTAINER

Jesse T. Littleton, Corning, N. Y., assignor to
 Corning Glass Works, Corning, N. Y., a corporation of New York

Application June 18, 1934, Serial No. 731,205

8 Claims. (CL 215—13)

This invention relates to vacuum insulated containers and more particularly to such a container which is provided with an opening at each end.

5 Vacuum insulated containers, commonly called vacuum bottles, are usually constructed of an inner blank commonly known as an inner piston and an outer blank commonly known as an outer piston, which blanks or pistons are formed with 10 bulbous portions and neck portions, the latter being sealed together at their outer ends in such a manner that a space is formed between the inner and outer pistons which is evacuated. This provides an effective insulation which prevents 15 the contents of the container from being affected by external atmospheric conditions. Sometimes it is desirable to employ a vacuum insulated container having an opening at each end in which case neck portions are formed at opposite ends 20 of the bulbous portions of the pistons and these neck portions are then sealed together in such a manner that access may be had to the interior of the inner piston from either end of the container. Such containers are, however, difficult to manufacture 25 as it is well known that after glass has been sealed it must be subjected to an annealing operation in order to release the strains introduced when the seal is made. The annealing of a glass article necessitates subjecting it to a temperature at or above its strain point and subsequently cooling it to atmospheric or its service 30 temperature at a predetermined rate which is calculated in accordance with the physical characteristics of the glass composition from which the article is made. With hollow vessels it is difficult 35 to obtain proper balance between the cooling rates of the internal and external portions and this difficulty is greatly magnified when the internal and external walls are separated from each other 40 as they are in vacuum insulated containers. As a result, double ended vacuum containers of the type to which this invention relates are subject to breakage during annealing due to the differences in expansion between the inner and outer 45 pistons. Moreover, such containers are apt to break in service owing to the fact that when a hot liquid, for instance, is introduced into the inner piston the latter will become heated and 50 expansion of the inner piston will take place while the outer piston is yet in its normal state. Hence the seals between the inner and outer pistons are strained and frequently such strains exceed the tensile strength of the glass with the 55 result that a crack or actual breakage will occur

which destroys the vacuum insulation and the entire container is then rendered useless.

The object of my invention is to overcome the difficulties heretofore experienced in the manufacture and use of vacuum insulated containers having openings at opposite ends. 5

The above and other objects may be accomplished by employing my invention which embodies among its features a vacuum insulated container in which the inner piston is made from 10 a glass having a coefficient of expansion which differs from that of the glass from which the outer piston is made.

Other features embody the use of graded seals between the inner and outer pistons when the 15 differences of expansion between them is so great that difficulty is experienced in effecting sealing the two different glasses together.

In the drawing:

Fig. 1 is a side view partly in section of a vacuum insulated container constructed in accordance with my invention; and

Fig. 2 is a fragmentary sectional view of a modified form of my invention.

Referring to the drawing in detail, a vacuum container designated generally 10 consists of an inner piston 11 and an outer piston 12 which are sealed together at opposite ends 13 and 14. The inner piston 11 is preferably formed from a glass having a coefficient of expansion which is slightly 25 below that of the outer piston 12 so that in cooling from the annealing temperature the outer piston will be thrown under a slight tension and the inner piston will be thrown under compression. This, then, produces a strained condition 30 in the vessel until the space 15 between the inner and outer pistons 11 and 12 has been exhausted when atmospheric pressure on the exterior of the outer piston 12 will tend to collapse it, thus exerting a compressive stress on it and counteracting 35 the tensile stresses which it previously possessed. Due to the tendency of the atmosphere to expand the inner piston 11 into the evacuated space, any compressional stresses which it previously possessed will be counteracted, at least to 40 some extent, and proper balance will be maintained with the result that breakage due to strain is less likely to occur. 45

In the modification shown in Fig. 2, the inner piston 18 of a vacuum insulated container designated generally 17 is formed of a glass having a 50 much lower coefficient of expansion than that from which the outer piston 18 is made, with the result that a direct and effective seal between the two glasses could not be made. Hence, I employ a 55

graded seal 19 between the inner and outer pistons and by so doing I am enabled to produce double ended vacuum insulated containers which will meet a wide variety of service conditions.

5 While in the foregoing there has been shown and described the preferred embodiment of my invention, it is to be understood that minor changes in the details of construction, combination, and arrangement of parts may be resorted to without departing from the spirit and scope 10 of my invention as claimed.

What I claim is:

15 1. A double walled container comprising an inner member and an outer member sealed together at the ends, the latter being formed of a material having an expansion coefficient which differs from that of the inner member.

20 2. A double walled container comprising an inner member and an outer member sealed together at their ends, the latter being formed of a material having a higher expansion coefficient than that of the inner member.

25 3. A double walled container comprising an inner member and an outer member, the latter being formed of material having an expansion coefficient which differs from that of the inner member and a graded seal between the inner and outer members.

30 4. A double walled container comprising an inner member and an outer member, the latter being formed of a material having a higher expansion coefficient than that of the inner member

and a graded seal between the inner and outer members.

5 5. A vacuum insulated container comprising an inner piston and an outer piston both the inner and outer pistons having neck portions at opposite ends, the inner and outer pistons being sealed together at the outer ends of the neck portion and being formed of glasses having different coefficients of expansion.

10 6. A vacuum insulated container comprising a glass inner piston having neck portions at opposite ends and an outer piston formed of a glass having a higher coefficient of expansion than that from which the inner piston is made and having neck portions at opposite ends, the outer ends of the neck portions being sealed together.

15 7. A vacuum insulated container comprising an inner piston of glass, an outer piston formed of a glass having a coefficient of expansion which differs from that from which the inner piston is made, both the inner and outer pistons having neck portions and graded seals joining the respective outer ends of the neck portions of the outer and inner pistons.

20 8. A vacuum insulated container comprising a glass inner piston having neck portions at opposite ends and an outer piston formed of a glass having a higher coefficient of expansion than that from which the inner piston is made and having neck portions at opposite ends, graded seals joining the respective outer ends of the neck portions of the outer and inner pistons.
